UNITED STATES PATENT OFFICE.

FRANK M. PETERS AND WARREN H. HUNGERFORD, OF CHICAGO, ILLINOIS, ASSIGNORS TO PETERS MACHINERY COMPANY, OF CHICAGO, ILLINOIS, A CORPORATION OF ILLINOIS.

PACKAGING APPARATUS.

Application filed July 6, 1920. Serial No. 394,117.

To all whom it may concern:

Be it known that we, FRANK M. PETERS and WARREN H. HUNGERFORD, citizens of the United States, residing at Chicago, in 5 the county of Cook and State of Illinois, have invented certain new and useful Improvements in Packaging Apparatus, of which the following is a specification.

Our invention has reference more particularly to a machine for forming a carton or container from a blank of cardboard or the like, and wherein the article or articles which are to be enclosed in the carton are inserted in the carton as the latter is being 10 formed, or are placed in position so that the blank is folded around such article or articles so as to form a carton containing such article or articles—thereby avoiding the necessity of filling the carton after it is 15 formed.

It is a common practice of manufacturers of bakery goods and the like, to put up their goods—for example, loaf cakes or quantities of wafers or small cakes—in cartons or individual packages, in which they 25 are sold to the consumer, and it is, of course, desirable to package the articles as rapidly as possible, to economize space, and minimize the expense of packaging the goods.

In packaging bakery goods, such as loaf cakes, wafers, and the like, it has heretofore been impossible to form the carton directly around the goods or articles to be contained therein, owing to the soft or brittle character 30 of the goods, which is likely to incur damage in the operation of forming the carton therearound, and also because of the irregular and not entirely uniform shapes of some of these goods which would render it 35 very difficult to fold the carton along straight lines and effect a neat appearing package. For these reasons it has been customary to fold the carton around a former of the proper size and shape, and after the 40 complete formation of the carton to fill the latter with the goods which it is intended to contain.

The principal objects of our invention are to provide a machine in which the operations of forming the carton and filling the latter are carried on at the same time so as 45 to avoid the necessity of separately making the carton and thereafter filling the same; to provide a machine in which a blank is

formed around the article or articles contained therein without danger of injury to such article or articles by the carton forming operations; to provide a carton forming device in which the article or articles to be packaged are placed so as to have the carton formed therearound and thus contain the articles when the carton is removed from the device; to provide a carton former which has the article or articles to be packaged placed therein before the blank is 55 formed therearound into a carton and having means for expelling such article or articles simultaneously with the carton from the former after the carton has been completed; to provide means for holding the 60 article or articles in the former before the carton is formed therearound; and, in general, to provide an improved machine operating automatically to receive successive charges of the goods to be contained in a 65 package and forming the carton therearound, so as to avoid the necessity of filling the carton after it has been formed.

For the purpose of illustration, we have shown our invention in connection with a 70 carton forming machine similar to that shown and described in United States Letters Patent 1,025,880 granted to F. M. Peters on May 7th, 1912, and

On the drawings, Figure 1 is a front view 85 of the machine of said patent with our invention applied thereto and the necessary modifications of said machine to adapt same to have our invention applied thereto.

Figure 2, a view looking at the right-hand side of the machine, shown in Figure 1, with the side frame removed and parts shown in section on the line 2—2 of Figure 1.

Figure 3, an enlarged detail view, partly 90 in section, showing the mechanism for folding and forming the carton.

Figure 4, a side view of the driving mechanism and devices for feeding the charge of goods to the carton forming head.

Figure 5, an enlarged detail view of the charge feeding mechanism showing the carton forming head in section and the charge feeding mechanism in the position just after a charge has been supplied to the carton 100 forming head.

Figure 6, a top view of the mechanism shown in Figure 5, and

Figure 7, a front view of the former with parts in section and other parts removed to disclose details of construction.

Inasmuch as the carton forming machine shown herein is essentially the same as that disclosed in the Peters' patent, hereinbefore mentioned, it is deemed unnecessary to describe in detail the construction of the carton forming machine except as to modifications thereof which our invention require.

This carton filling machine comprises the side frames 1, which are suitably spaced apart and have a top 2 mounted thereon and a cross-brace 3 connecting the side frames 15 below the top, and adjacent the front of the machine. An upwardly projecting standard 4 is mounted at each side of the machine, and a shaft 5 is journaled in the upper ends of these standards directly above a shaft 6, 20 which is journaled in the side frames 1 below the top 2. Each of these shafts has pairs of sprockets 7 and 8, respectively, secured thereon and around which pass the endless chains 9 which are carried by these sprockets 25 7 and 8, one at each side of the machine, as shown in Figure 1. The chains 9 are connected together at certain intervals by cross-bars 10, the ends of which project beyond the chains and slide in guideways 11 at opposite 30 sides of the front of the machine, which guides project a considerable distance above and below the top 2 of the machine. Each of the bars 10 carries a carton forming head, indicated as a whole at 12, these heads being 35 of special construction, as required by our invention, and arranged as they move downwardly at the front of the machine to first receive a charge of the article or articles to be enclosed in the carton and then have the 40 carton blank formed therewith into a carton and then have the carton blank together with the charge of the article or articles contained therein ejected from the forming head.

The top 2 of the machine has an opening 13 therein through which the forming heads 12 pass in their downward movement, and on the top 2 a carton blank, and lining therefor, if desired, is placed previous to the passage 50 of each head 12 through the opening 13, so that the blank is formed around the head in the form of a carton as the head continues to descend below the top 2. The mechanism for accomplishing the formation of the carton is substantially the same as that shown 55 in the Peters' patent above referred to, and comprises a plate 14 which is mounted along the front edge of the opening 13 on an oscillatory shaft 16, which latter is operated by the cam 17 on the shaft 15 through suitable 60 connections whereby the plate 14 is thrown upwardly at the time that the carton forming head 12 starts to enter the opening 13 and thereby folds up the portion of the carton blank which constitutes the front wall of the

carton. The plate 14 has a wing 19 pivoted at each end thereof and operated by the cam 20 on the shaft 15 through the link 123 which is connected to a crank 124 on the shaft 125, the latter being provided with a crank 126 70 which has the slotted outer end connected to an arm of the bell crank 127 which is pivoted at 128 on the front plate 14 and has the other arm pivoted to the inner ends of the levers 129, said levers being oscillatively mounted on the plate 14 and having their outer ends pivoted to the wings 19. The cams 17 and 20 are arranged so as to swing the wings 19 upwardly and rearwardly as the plate 14 is raised to the upright position and thereby 80 fold the end flaps, on the front wall of the carton, back alongside the forming head 12. Immediately after the front plate 14 and side wings 19 have been folded against the lower end of the forming head, the forming head begins to pass between the side plates 122 which are positioned so as to engage close against the ends of the forming head 12 and have their upper ends rounded outwardly so that, as the forming head carries the carton blank down therebetween, the end flaps on the carton bottom are folded up thereby 85 against the end flaps of the front wall which have just been folded into position by the side wings 19. At about the same time, the fingers 130 which are pivoted on a cross bar 131 of the frame are operated by the cam 132 on the shaft 5 through the bell crank 133 and links 124 to move downwardly towards each 90 other and engage the protecting lining of the carton at the juncture of the carton back with the end flaps and thereby hold the said lining distended for the subsequent folding operation. The top 2 at the rear of the opening 13 has an inclined entrance 21 thereto 100 which serves, as the forming head carries the carton blank down through the opening 13, to fold the back and cover portion of the carton up against the rear wall of the forming head 12, and at each end of the opening 13 and extending downwardly from a point somewhat below the inclined entrance 21 is a 105 guide 22, having the upper end beveled forwardly and inwardly to afford a gradual deflecting surface, which folds the end flaps 23 of the carton blank in against the other previously folded end flaps of the carton blank as the carton forming head continues to move downwardly. The passageway 110 through which the carton forming head 12 passes is cut away at the rear somewhat below the inclined entrance 21 so as to permit the rear wall and cover portion of the carton to swing rearwardly, as shown in Fig. 3, so as to rest against the inclined wall 24, such 115 rearward throw being positively effected by a pair of fingers 25, one at each side of the opening through which the forming head passes, and which are operated by the cams 26 on the shaft 15 at the proper time to 120 125 130

swing upwardly to the angular position, as shown in Fig. 3, so as to engage the lower ends of the locking tongues 27 of the carton, and thereby insure rearward throwing of the back and cover portions of the carton blank, and also guide the tongues 27 to the proper position for insertion in the slots 28 provided therefor in the end flaps of the front wall portion of the carton. As soon as the carton reaches this position, the rollers 29 at opposite sides of the forming opening are thrown inwardly by the operation of the cams 30 on the shaft 18, and immediately thereafter the plate 31 against which the back of the carton rests and which is hinged at 32, is thrown to the upright position by the operation of the cam 33 on the shaft 6, which operation forces the locking tongues 27 between the rollers 29 and the end flaps of the carton, and by reason of openings 34 being provided in the ends of the carton forming head, the rollers 29 press the locking tongues 27 and portions of the end flaps inwardly above the slot 28 so that the straightening up of the supporting plate 31 forces the tongues 27 down through the slots 28 and locks the carton in the completely formed position, after which it is carried downwardly on the forming head 12 until it clears the carton forming mechanism and is then ejected from the head.

The shaft 15 has a spur gear 35 on the end which meshes with the spur gear 36 on the shaft 6, the latter gear being twice the diameter of the former, so that the shaft 6 makes a half revolution, while the shaft 15 makes a complete revolution; and in our machine the shafts 6 and 15 have an intermittent or step by step movement imparted thereto, instead of the continuous movement as in the structure of the Peters' patent, this change being required in order to afford intervals of rest of the forming heads 12, during which a change of material to be placed in the package may be inserted in the forming head. To effect this step by step movement, the drive shaft 37, which is mounted in the side frames 4 with the drive pulley 38 thereon at one end, is provided with a Geneva drive connection with the shaft 6 comprising the disc 39 on the shaft 37, which disc is cut away, as at 40, and provided with an arm 41 having a pin or roller 42 at the outer end which is adapted to engage successively in the four radial slots 43 of the Geneva wheel 44, so that the latter and its shaft 45 make a quarter turn at every revolution of the shaft 37, the rotation of the shaft 45 being effected during substantially a quarter turn movement of the shaft 37, so that during substantially three-quarters of each rotation of the latter, the shaft 45 and mechanism operated thereby are inactive. The carton forming heads 12 are spaced apart on the chains 9 a distance equal to one-half of the circumfer-

ence of the wheels 7 or 8, and it is therefore necessary to advance the heads 12 such distance during each period of the step by step movement, and to effect this result there is a spur gear 46 on the shaft 45 which meshes with a spur gear 47 on the shaft 6, said latter gear being one-half the diameter of the former, so that at each quarter revolution of the shaft 45, the shaft 6 makes a half revolution and the shaft 15 through gears 36 and 35 a complete revolution, which is the extent of movement of each required to effect all the operations for completely forming the carton from the blank.

The carton forming head 12, in accordance with our invention, is adapted to have a charge of the articles inserted therein, which are to be contained in the finished carton, and to this end the forming head is composed of a sheet metal shell with the walls made as thin as possible without sacrificing the required strength of the forming head, thus enabling the carton blank to be folded close to the articles to be contained therein and avoid unnecessary looseness of the articles in the finished carton. The side and rear walls 48 and 49 of the forming head extend full length of the forming head, the former walls being provided with the openings 34 therein, hereinbefore referred to, and having lugs 50 at their upper ends whereby the forming block is secured to the cross-bar 10 on the chains 9. The lower portion of the front wall 51 of the carton forming head is cut away, as indicated at 52, so as to admit a charge of the articles such as the wafers 53, as indicated in Fig. 7, loaf cake or the like, into the lower end of the forming head, and there is a conveyor mounted adjacent one of the positions of rest of the forming heads from which successive charges are adapted to be applied to each forming head 12 as they come to rest adjacent the conveying mechanism.

The conveying mechanism and mechanism for filling the forming head are in the present illustration located at the position of rest of the carton forming head immediately preceding the passage thereof through the carton forming mechanism, and comprise a conveyor bottom 18 arranged directly at the front of and with the upper surface thereof substantially in the same plane as the lower edge of the forming block 12 when the latter is at rest. The upper surface of the conveyor bottom 18 is provided with a longitudinal groove 53 to receive the chain 54 therein, which latter carries a series of flights 55 which are spaced apart a suitable distance to receive the proper charge for the carton therebetween. The charges are applied to the conveyor in any suitable manner, either manual or otherwise, and the chain and flights 130

are advanced in a step by step manner at the same time that the forming heads 12 are so advanced. For this purpose, the chain 54 may be connected in any suitable manner for operation by either of the shafts 6, 15 or 45, an example of which is shown in Fig. 1, wherein the shaft 6 has a bevel gear 56 meshing with the bevel gear 57 on the lower end of the shaft 58, which shaft 10 has a bevel gear 59 on the upper end meshing with the bevel gear 60 on the shaft 61 which carries the sprocket 62, over which the conveyor chain 54 passes.

For inserting the charge of goods from the conveyor into the lower end of the forming block 12, a pusher 63 is mounted in guideways 64 of the brackets 65 so as to reciprocate transversely of the directional movement of the conveyor and at a distance 20 thereabove, and this pusher has upright guides 66 at the forward end in which a plate 67 is mounted for vertical movement and adapted to be depressed to a position along side of a charge of material on the 25 conveyor, so that inward movement of the pusher 63 causes said plate to engage the outer side of the charge of material between adjoining flights 55 of the conveyor, and push same laterally off the conveyor bottom 30 52 into the lower end of the forming block. A bell crank lever 68 is pivoted at 69 to the outer end of the pusher 63 and has one arm forked, as at 70, to straddle the pin 71 between lugs on the rear face of the plate 35 67. The other arm of the bell crank lever 68 has a pin engaging in the slot 72 of the crank arm 73 on the shaft 74, which latter is journaled in the brackets 65 and projects outwardly at one side of the machine and is 40 there provided with a crank arm 75 which has the outer end pivoted to one end of the link 76, the other end of which said link is bifurcated and straddles the shaft 37 and has a roller 77 thereon which engages in a 45 cam groove 78 in the face of the cam disc 79 on the shaft 37 whereby the crank 68 is oscillated to force a charge of material from the conveyor into the forming block during the time that the shaft 45 and mechanism 50 operated thereby is inactive.

It is necessary to have the bottom of the forming block open to permit the charge of material to be ejected from the forming block after the carton has been formed 55 therearound, and a temporary bottom is required for the forming blocks, in case they are filled during the descending movement, to support the charge of material as it is inserted in the forming block and before it is gripped by the holding members, hereinafter referred to. This bottom or temporary closure is indicated at 80 and is hinged at 81 to the inner edge of the conveyor bottom 52 so as to swing up and form 60 a continuation of the upper surface of the

conveyor bottom 52 directly under the charge-containing cavity in the lower end of the forming head 12, this bottom being provided with a crank arm 82 which is connected by the link 83 with the arm of a bell crank 84 which is pivoted at its angle to the brackets 65 and has a roller 86 at the outer end of the other arm adapted to be engaged by the rib 87 on the pusher 63, which rib has the inner end tapered, as indicated at 88, so as to force the roller 86 downwardly as the pusher 63 begins its inward movement and hold same in the depressed position until the pusher returns to the initial position. The forcing of the roller 86 downwardly oscillates the bell crank 84 and thereby swings the bottom or closing member 80 up to the horizontal position shown in Fig. 5, just before the charge is inserted from the conveyor into the forming block, and said bottom is released by the pull of the spring 85 as soon as the pusher 63 is withdrawn so that the rib 87 disengages the roller 86.

For holding the charge of material in the forming head after the bottom 80 is swung downwardly and as the forming head continues its downward movement, a thin plate 90 is provided at each end of the forming block, offset as at 121, so as to normally lie within the opening 34 in the end wall and adapted to clamp against the opposite ends of the charge after the latter has been inserted in the forming block. Each plate 90 is secured at its upper end to a corner bracket 91 which is pivotally mounted on a shaft 92, the ends of which are mounted in bearings provided therefor in the front and rear walls 51 and 49, respectively, of the forming block, and each corner bracket 91 has a spring plate 93 extending inwardly so that the ends thereof overlap, and normally held downwardly by the springs 120 on the end walls of the forming heads. A shaft 94 extends from front to rear of the forming block and has the ends journaled in bearings 95 provided therefor on the inner face of the front and rear walls 51 and 49, respectively, and there is a cam 96 on this shaft directly underneath the overlapped ends of the spring strips 93 and provided with an eccentric flat surface, shown by dotted lines in Fig. 7, which upon rotation of the shaft 94 elevates the inner overlapped ends of the spring strips 93 and holds the shaft 94 against accidental displacement from this position of adjustment. The elevation of the inner ends of the spring strips 93 causes the side wings 90 to swing inwardly, and in case a charge of material is in the forming block, the ends of the charge are engaged by the side wings 90 so as to be held in the forming block.

The operation of the shaft 94, to elevate the spring strips 93, just after the charge

has been inserted in the forming block, is preferably effected by the mechanism which inserts the charge, and to this end the front wall 51 of the forming block is provided 5 with a slot 97, and the shaft 94 has a finger 98 fixed thereon just inside the wall 51 in position to be engaged by a lug 99 which projects from the face of the plate 67. Obviously, when the shaft 74 is oscillated to 10 insert a charge of material into the lower end of the forming block, the first effect of such oscillation is to oscillate the bell crank 68 on its pivot 69 and thereby slide the plate 67 downwardly to a position at the 15 side of the charge of material on the conveyor. When the plate 67 reaches the limit of its movement, the further oscillation of the shaft 74 causes the pusher 63 to move bodily toward the forming head until the 20 charge is fully inserted, and by such movement, while the plate 67 is in the lowermost position, the lug 99 is projected through the lower end of the slot 97 directly below the trigger 98, as shown in Fig. 5. After the 25 charge has been inserted and the shaft 74 is oscillated in the reverse direction to withdraw the charge-inserting mechanism, the first operation is the oscillation of the bell crank 68 which raises the plate 67 to the 30 upper extremity of its movement, thereby causing the trigger 98 to be lifted by the lugs 99 in such a manner as to rotate the shaft 94 and turn the cam 96 and thereby elevate the inner extremities of the spring 35 strips 93, so that the end wings 90 grip and hold the charge of material in the lower end of the forming block. As soon as the plate 67 reaches the upper extremity of its movement and after the operation of the 40 trigger 98, as aforesaid, the further oscillation of the shaft 74 withdraws the pusher 63 to the initial position preparatory to the insertion of another charge, and as the pusher 63 nears such initial position the rib 45 87 thereof moves out of engagement with the roller 86 and permits the door 80 to drop down before the operation of the mechanism takes place to advance the forming blocks 12 another step in their intermittent movement. 50

Before the forming head moves downwardly from the filling position, a carton blank is placed in the proper position on the top 2 of the machine and may also have the 55 usual waxed paper lining placed thereupon if desired. As the forming block, which has just been filled, now moves downwardly, it comes into engagement with the carton blank, and the mechanism, hereinbefore mentioned, forms the carton and the lining, 60 if such lining is employed, around the forming head 12 as it passes downwardly through the opening 13 in the top plate and passes the carton forming and locking members 14, 65 19, 121, 22, 25, 29 and 31, which completely

form the carton blank into a carton around the forming block and the charge of material contained therein. A conveyor 100, of any suitable type, is provided directly below the downwardly moving forming blocks 12 70 to receive the cartons thus formed and the charge of material contained therein and convey same away. For the purpose of ejecting the carton and its contents, as the forming block nears the lowermost position 75 of its movement and before it begins to make the turn around the lower sprockets 8, we have provided an ejecting mechanism to insure ejection of the charge, together with the carton, and this mechanism takes the 80 place of the ejecting mechanism which is provided for ejecting the carton in the machine of the Peters' patent, hereinbefore mentioned. This ejection mechanism comprises a platen 101 extending across the 85 forming block directly above the chamber thereof in which the charge is inserted. This platen is mounted on a stem 102 which slides in a bearing 103 formed on or attached to the rear wall 49 of the forming block, and the platen is held in an elevated position by a pair of springs 104, which have their opposite ends connected respectively to the top of the platen and hooks 105 projecting inwardly from the rear wall of the former. 90 The elevation of the platen is limited by a collar 106 which is fixed on the stem 102 below the bearing 103 and engages the latter when the platen is in the elevated position. The upper end of the stem 102 is bifurcated 95 and has a pin 107 passing through a slot 108 in the end of a lever 109, which latter is pivoted intermediate of its ends between a pair of lugs 110 on the upper edge of the supporting bar 10 and is positioned directly 100 above the bar 10, so that the passageway provided through the forming mechanism for the bar 10 will also admit the lever 109 therethrough. The outer end of the lever 109 is preferably offset and provided with 105 a roller 111 which, as the forming block with its charge and the carton formed therearound approaches the lower extremity of its movement, engages a trip lug 112 on one of the guides 11, causing oscillation of the 110 lever 109 so as to force the platen 101 downwardly and discharge the carton and its contents onto the conveyor 100. Obviously, it is necessary to release the charge-holding 115 wings 90 as the ejecting operation takes place, and it is for this reason that the slotted connection of the stem 102 with the lever 109 is provided—that is, in order to give the lever 109 a preliminary movement without operating the platen 101, during 120 which preliminary movement the side wings 90 are released. To accomplish this result, the shaft 94, which carries the cam 96, has a second trigger 113 thereon which, when the cam 96 is turned to the position in which 125 130

the inner ends of the spring strips 93 are elevated, comes in position to be engaged by the lower end of the stem 114, which latter has the upper end pivoted at 115 to the lever 109 and the lower end mounted to slide 4 the bearing 116 provided therefor on the rear wall 49 of the forming head so as to hold the lower end of the stem directly above the trigger 113. Obviously, as the lever 109 is rocked, the stem 114 is projected downwardly, and by its engagement with the trigger 113, rotates the shaft 94 to disengage the elevated portion of the cam 96 from the spring strips 93 and thereby release the holding wings 90 from pressure against the ends of the charge, and immediately following this release, the end of the slot 108 engages the pin 107 of the stem 102 and forces the platen 101 downwardly and thereby discharges the carton and its contents from the forming head onto the conveyor 100. After the roller 111 passes beyond the trip lug 112, and the ejection of the package and its contents has been completed, the platen 101 is returned to the normal position by the springs 104 and the lever 109 also returns to the normal position.

In case the machine is being used in connection with frosted cakes, the ejecting mechanism of the aforesaid Peters' patent may be employed, instead of the ejecting mechanism just described, as the latter is liable to damage the frosting, and the structure of the Peters' patent will readily accomplish the ejection of the cake and carton as the weight of the cake insures same leaving the forming head with the carton.

It is to be understood that we have described our invention in connection with a machine similar to that shown in the Peters' patent merely for the purpose of affording a clear understanding of the application of our invention to a carton forming machine, but we contemplate using the invention in connection with any type of carton forming machine to which it is capable of being applied. It is also contemplated that in a machine similar to that illustrated and described, the filling operation may be arranged to take place while the forming blocks are moving upwardly, instead of downwardly, in which case the temporary bottom 80 and the mechanism for operating same may be dispensed with. There are also other numerous changes and modifications which may be made without departing from the principles of our invention, and we therefore do not propose limiting the patent granted herein, otherwise than necessitated by the prior art.

We claim as our invention:

1. In a device of the class described, the combination of a forming head having a compartment therein, carton folding mechanism for forming a carton on the head, and

means operable prior to the formation of the carton to lock a charge of material in the compartment and operable after the formation of the carton to release said charge of material.

2. In a device of the class described, the combination of carton folding mechanism, a carrier co-operating with said mechanism to fold a carton around a charge of material, and means on the carrier operable automatically to engage and hold the charge of material as the carton is formed therearound and thereafter release said charge.

3. In a device of the class described, the combination of a forming head having a compartment therein, carton folding mechanism for forming a carton on the head, feeding mechanism for inserting a charge of material into said compartment, and releasable means for yieldingly holding the charge in said compartment.

4. In a device of the class described, the combination of a forming head having a compartment, carton folding mechanism, means for passing the head through the carton forming mechanism, feeding mechanism for inserting the charge of material into the compartment of the forming head, and means on the forming head operable before the formation of the carton thereon to yieldingly hold the charge in the compartment and operable after the formation of the carton to release the charge of material.

5. In a device of the class described, the combination of a forming head, carton folding means co-operating therewith to form a carton on the head, means for inserting a charge of material into the forming head, holding members on said head for engaging and holding the charge of material therein, a cam, and means for operating said cam to alternately lock and release the holding members.

6. In a device of the class described, the combination of a forming head, means for applying and folding a blank around the head so as to form a carton, a conveyor for advancing charges of goods successively to a position adjacent the forming head, means for transferring a charge from the conveyor to the forming head, and mechanism for operating the conveyor and said means alternately.

7. In a device of the class described, the combination of a forming head, means for folding a blank around the head so as to form a carton, feeding mechanism for introducing a charge of goods into the head before the formation of each carton therearound, and means, automatically operable, to lock the charge in the forming head during the formation of the carton.

8. In a device of the class described, the combination of a forming head, means for folding a blank around the head to form a

carton, a conveyor for supplying charges of goods successively to and inserting same into the forming head, and a pair of opposed gripping members adapted to be held 5 at a tension against the ends of the charge of goods in the forming block preparatory to the formation of the carton therearound.

9. In a device of the class described, the combination of an endless carrier having a 10 plurality of forming blocks thereon, means adjacent the path of the carrier and adapted to co-operate with the forming blocks to fold a blank therearound and form a carton, a conveyor adjacent the path of the 15 forming blocks for supplying successive charges of goods to be enclosed in the carton, means for automatically transferring the charges to the forming blocks, and an ejector for removing the charge and carton 20 simultaneously from the forming blocks.

10. In a device of the class described, the combination of an endless carrier provided with mechanism for imparting a step by step movement thereto, a plurality of forming heads on the carrier, mechanism adjacent the path of the carrier for forming a blank around each forming head into a carton, a conveyor adapted to supply charges of goods successively to a position adjacent the path of the forming heads, means operable during intervals of rest of the carrier for transferring a charge of goods from the conveyor to the forming head, an ejector on each forming head, and means adjacent the path of the carrier for operating the ejector, 25 after the formation of the carton, so as to remove the carton and the charge of goods from the head. 30
